SUSPENSION RAILWAY TOY TRAIN

Arthur J. Di Stasi, Trenton, N. J.

Application November 23, 1953, Serial No. 27,732

Term of patent 14 years

(Cl. D34—15)

To all whom it may concern:

Be it known that I, Arthur J. Di Stasi, have invented a new, original, and ornamental Design for a Suspension Railway Toy Train, of which the following is a specification, reference being had to the accompanying drawing, forming a part hereof, wherein:

Fig. 1 is a fragmentary perspective view of a suspension railway toy train embodying my new design, showing the forward portion of the train; and

Fig. 2 is a fragmentary perspective view thereof, showing the rear portion of the train. The sides not shown have substantially the same appearance as the sides shown in Figs. 1 and 2.

The characteristic features of my new design reside in the portions shown by means of full lines in the drawing.

I claim:

The ornamental design for a suspension railway toy train, substantially as shown and described.
